UNITED STATES PATENT OFFICE.

WILLARD T. SEARS, OF HARTFORD, CONNECTICUT, ASSIGNOR TO PRATT & WHITNEY COMPANY, OF HARTFORD, CONNECTICUT, A CORPORATION OF NEW JERSEY.

RADIAL DRILL.

1,089,442.

Specification of Letters Patent. Patented Mar. 10, 1914.

Application filed January 25, 1913. Serial No. 744,087.

To all whom it may concern:

Be it known that I, WILLARD T. SEARS, a citizen of the United States, residing at Hartford, in the county of Hartford and 5 State of Connecticut, have invented certain new and useful Improvements in Radial Drills, of which the following is a specification.

This invention relates to radial-drills, one 10 of the primary objects of the invention being to provide effective means for adequately supporting the rotary column in such way that the same can be freely turned for adjustment when required, and for also solidly 15 and substantially maintaining said column in an adjusted relation when necessary.

In the drawings accompanying and forming part of the present specification I have shown in detail one of the several convenient 20 forms of embodiment of the invention which I will set forth fully in the following description to enable those skilled in the art to practise the invention. I do not limit myself to this disclosure; I may depart 25 therefrom in several respects within the scope of the invention defined by the claims following said description.

Referring to said drawings: Figure 1 is 30 a side elevation of a radial-drill involving the invention. Fig. 2 is a detail view with a portion broken away to show the internal construction, of a base. Fig. 3 is a horizontal section on the line 3—3 of Fig. 1, and, Fig. 4 is a vertical section on the line 35 4—4 of Fig. 3.

Like characters refer to like parts throughout the several figures of the drawings which it will be observed are on different scales.

40 The machine shown involves in its construction a base or bed as 2 and a column as 3, the latter as will hereinafter appear being turnable about a vertical axis. Mounted on and rigidly secured to the base 45 in some desirable manner as by bolts 4, is a foot-piece 5, and the base or bed 2 and this footpiece 5 jointly present a suitable support for the column 3 which is shown provided with the spindle-supporting arm 50 6 furnished with the usual accessories which form no part of the present invention and hence require no description.

The footpiece 5 as illustrated is in the 55 form of a shell receiving for rotation the lower portion of the column 3 which as will

hereinafter appear, has a bearing at several places against its supporting means. The footpiece or shell 5 is shown having an inwardly extending flange 7 at its top which as will be hereinafter set forth is provided 60 with a column-sustaining track. The inwardly extending flange 7 is furnished with a pendent or vertically disposed flange 8 to receive the cylindrical journal portion 9 of the column 3 which, as will be clear, has a 65 turning contact in the annular flange or sleeve 8, this being one of the several bearings for the column. It may, of course, not always be necessary to provide several of such bearings, although greater rigidity is 70 insured when they are present. The lower cylindrical portion 10 of said column is fitted for turning movement in the annular flange or band 11 at the center of the disk or plate 12 fastened at or near its margin 75 by screws 13 or otherwise, to the upper surface of the base or bed 2, said upper surface being concaved or dished as at 14 to receive the lower end of the column 3 and the band or flange 11. This band 11 provides a sec- 80 ond bearing for the column. Said column near its lower end is rabbeted or channeled as at 15, to receive the ring 16 fastened as by screws 16' to the column, the active sur- 85 face of this ring 16 being on an outward downward taper to coöperate with a similar taper or cone surface on the divided or split clamping ring 17 surrounding the column and having a bearing against the 90 annular flange 18 in the footpiece 5.

As will hereinafter appear the column is equipped with an anti-friction roller which has a yieldable engagement with the support for said column, and although this yieldable engagement can be secured in sev- 95 eral ways, I prefer that it be accomplished by yieldingly mounting the roller. Al- though this roller may be located at any desirable point, I prefer that it be substan- tially coincident with the center of gravity 100 of the column structure; that is, the column and the parts carried by and movable there- with, to thus secure the best results.

There is shown set in the upper part of the footpiece 5 an annular track or runway 105 19, the flange 7 having a circular groove 20 to receive said track which is to be traversed during rotary adjustments of the column 3, by anti-friction means on the column, said 110 anti-friction means consisting preferably of

a single frusto-conical or tapered roller 21 preferably yieldingly supported by said column. In the showing made the apex of the cone defining the operative surface of the roller 21 is coincident approximately with the axis of rotation of the column, so that easy turning movement of said column is insured. The conical roller 21 is carried by a stud 22 supported by the branches of a fork 10 on the outer approximately-horizontal arm of the angle lever 23 pivoted at its angle at 24 in a slot or aperture in the column, the depending or vertical arm of the angle lever having an adjusting screw 25 bearing 15 against the innermost one of several superimposed bowed springs 26 overlying the slot 27 in the column 3, so that the necessary resiliency of the spring means is obtained. By the adjustment of the screw 25 the tension 20 of the spring means against the lever 23 can be regulated. The springs 26 acting against the tail portion of the lever 23 maintain the roller 21 yieldingly against the track 19 to put the flange 28 in very light contact with the upper edge of the footpiece 5, so that when this relation is present the column 3 can be readily turned for purposes of adjustment.

To hold the column in an adjusted position it is clamped to its support in some suitable manner as by the wedge ring 17 which when contracted tends to force down the companion ring 16 by reaction against the flange 18, to clamp the flange 28 of the column 3 solidly against the footpiece 5. The ring 17 at its terminals is provided with outwardly extending ears 29 having opposite threads to receive the oppositely threaded portions of the screw 30. It will be apparent that when the screw is turned in one direction the ring 17 will be contracted, so that its wedge or cone portion will tend to draw the ring 16 downward, while when turned in the opposite direction the ring 16 is freed. To operate the screw and therefore the divided actuating band 17 I provide electrical means, the solenoid 31 being shown for this purpose, the armature of said solenoid being connected with the arm 32 fastened as by the screw 33 to the adjusting screw 30. When the solenoid 31 is energized, the lever or arm 32 will be drawn upward to contract the ring 17 while deenergization of the solenoid permits the expansion of said ring 17.

What I claim is:

1. The combination of a support, a rotary column carried by the support, a roller carried by the column, means for yieldingly forcing the roller toward the support, and means for drawing the column into rigid engagement with the support and at the

same time causing the relative retraction of the roller.

2. The combination of a support, a rotary column carried by the support, a circular track on the support, a single conical roller carried by the column, to travel in contact with said circular track, means for yieldingly forcing the roller toward the support, and means for drawing the column into rigid engagement with the support and for causing at the same time the relative retraction of the roller sufficient to permit the column to come into clamping engagement with the support.

3. The combination of a support, a column structure rotatively carried by the support, a circular track on the support, and a single conical roller on the column to travel in contact with said support, and situated approximately at the center of gravity of said column and the parts supported thereby.

4. The combination of a support, a rotary column carried by the support, a wedge ring rigid with said column, a divided wedge ring active when contracted to act against the first wedge ring, to clamp said column to said support, and means comprising an electrically operated device for contracting said second wedge ring.

5. In a radial drill, the combination of a support, a rotary column carried by said support, a circular track on the column, a single-conical roller, a yieldingly mounted lever on the column, upon which said roller is mounted, said lever being adapted to move said roller toward said column, and means for clamping said column to said support and at the same time for causing the relative retraction of the lever and thereby the roller sufficient to permit the column to come into clamping engagement with the support.

6. The combination of a support, a rotary column carried by the support, a circular track on the support, a single conical roller to travel in contact with said track, a lever pivotally mounted between its ends, said roller being rotatively connected with one branch of the lever, spring means acting against the other branch of said lever, to force said roller yieldingly toward said support, and mechanism for clamping said column rigidly to said support and at the same time causing relatively the retraction of said lever and thereby the roller sufficient to permit the column to come into clamping engagement with the support.

In testimony whereof I affix my signature in presence of two witnesses.
